UNITED STATES PATENT OFFICE.

JOHN C. KOPF, OF BELLEVUE BOROUGH, PENNSYLVANIA, ASSIGNOR TO THE DUFF MANUFACTURING COMPANY, OF PITTSBURGH, PENNSYLVANIA, A CORPORATION OF PENNSYLVANIA.

SCREW JACK.

1,413,229.

Specification of Letters Patent. Patented Apr. 18, 1922.

Application filed August 2, 1920. Serial No. 400,802.

To all whom it may concern:

Be it known that I, JOHN C. KOPF, a citizen of the United States, and resident of the borough of Bellevue, in the county of Allegheny and State of Pennsylvania, have invented a new and useful Screw Jack, of which the following is a specification.

The invention relates to screw-jacks of the kind in which a hollow cylindrical jacking member is slidably guided in a bearing in the top of an enclosing base frame, on the bottom of which the lifting screw is rotatably supported, and comprises an improved and inexpensive construction whereby the bearing is protected from dirt and grit, while being utilized for a positive stop to prevent over-lifting.

In the accompanying drawings forming a part hereof:

20 Figure 1 is a vertical section of a journal-box jack embodying the invention, showing the jacking member in its lowered position;

Fig. 2 is a vertical section at right angles to Fig. 1 through the upper part of the frame, showing the jacking member, in elevation, in fully raised position;

Fig. 3 is a cross-section on the line 3—3 of Fig. 2; and

Fig. 4 is a bottom plan of the jacking member and nut.

The hollow frame or bell is designated 1; and 2 is its inwardly projecting top bearing. A hollow cylindrical jacking member 3 slides in this bearing, wherein it is prevented from 35 turning by a key 4 in the bearing cooperating with a vertical slot 5 in the side of the jacking member.

The jacking member is actuated by a vertical screw 6, rising from the base, on which 40 it is rotatably supported by a ball-bearing

7. The screw in turn is operated from a horizontal operating shaft 8 journaled in a bearing 9 in the frame, and having a bevel pinion 10 on its inner end, meshing a bevel 45 gear 11 keyed to the plain lower end 12 of the screw.

The screw extends upward within the jacking member, through a nut 13, which is inserted in a cavity in the bottom of the 50 member, against an internal supporting shoulder 14. The lower end of the nut both projects below the jacking member and extends outward beyond the periphery thereof, so as to form a continuous stop

flange 15, which may be omitted, however, 55 at the side adjacent the driving pinion. This flange, when the jacking member is raised to the limit, as seen in Fig. 2, abuts the bottom ledge of the top bearing and absolutely prevents further movement, the 60 strain, however, falling on the separate nut, the jacking member being merely sustained by the arrested nut.

The combined member has a second enlargement, consisting of a head 16 which 65 laterally overhangs the top opening of the bearing 2 sufficiently to close the same against admission of grit when the jack is in its normal or retracted condition, at which time a journal-box jack, for example, may 70 be lying with the coal in the tender, or in some other equally dirty spot. Such head can be quite small and made to fit the mouth of the bearing; and the two parts, namely 75 the nut and jacking member, with their integral projections at opposite ends, can be manufactured economically, and secure the double advantages indicated.

In assembling the jack, the jacking member is introduced through the top of the 80 frame, and the nut is then pressed upward into the lower end of the member, where it is held against rotation by a pin 17.

What is claimed as new is:

1. A jack comprising a hollow base frame 85 having a bearing at its upper end, a lifting screw rotatably supported on the bottom of said frame, a hollow cylindrical jacking member slidably guided in said bearing and formed at the top with an enlargement constituting a bearing closure, and a nut inserted into the lower end of the jacking member and formed with a stop to coact 90 with the bottom of the bearing.

2. A jack comprising a hollow base frame 95 having a bearing at its upper end, a lifting screw rotatably supported on the bottom of said frame, a hollow cylindrical jacking member slidably guided in said bearing and formed at the top with an enlargement constituting a bearing closure, and a nut inserted into the lower end of the jacking member, the lower end of said nut projecting below the jacking member and extending laterally beyond the periphery thereof in the 100 form of a stop flange.

3. A jack comprising a hollow base frame having a bearing at its upper end, a lifting

screw rotatably supported on the bottom said frame, a hollow cylindrical jacking member slidably guided in said bearing and formed at the top with an enlargement constituting a bearing closure, and a nut inserted into the lower end of the jacking member, the lower end of said nut projecting below

the jacking member and extending laterally beyond the periphery thereof in the form of a stop flange, said stop flange being omitted at one side, and means locking the nut in position in the jacking member.

JOHN C. KOPF.
